UNITED STATES PATENT OFFICE.

RUFUS J. MORTON, OF GREENSBORO, NORTH CAROLINA.

ADVERTISING DISPLAY-STAND.

1,388,745.

Specification of Letters Patent. Patented Aug. 23, 1921.

Application filed June 8, 1920. Serial No. 387,331.

To all whom it may concern:

Be it known that I, RUFUS J. MORTON, a citizen of the United States of America, residing at Greensboro, in the county of Guilford and State of North Carolina, have invented new and useful Improvements in Advertising Display-Stands, of which the following is a specification.

The object of the invention is to provide an attractive advertising or display stand adapted for holding in spaced relation, advertising cards or display signs, and having in connection therewith a movable indicating means and an automatic signal for directing attention to the stand to call the attention of observers to the displayed signs co-incidently with the operation of the indicating means with a general purpose of emphasizing the subject matter of the signs to impress the same upon the memory of the observer or beholder, and with these objects in view, the invention consists in the construction and combination of parts, of which a preferred embodiment is shown in the accompanying drawings, wherein:

Figure 1, is a front view of a display stand embodying the invention.

Fig. 2, is an edge view of the same.

Fig. 3, is a detail view showing the alarm mechanism.

Fig. 4, is a front view of a modified construction of the stand.

Fig. 5, is an edge view of the construction shown in Fig. 4.

The device consists essentially of a rack adapted for and provided with suitable means for supporting advertising signs or cards, the sign supporting surface of the same being traversed by movably connected

elements actuatable either continuously or intermittently by a suitable motor as of the wind driven or windmill type in connection with an alarm or signal mechanism actuatable at intervals to attract attention to the

stand and hence through the indicating means to the signs supported thereby. In the construction illustrated, in Figs. 1 and 2 and 3, inclusive, the rack 10 is provided with supporting board or surface 11 which

50 may be divided into spaces as indicated for the reception of the signs or cards, said rack being adapted for location and erection at any suitable vantage point as for example in front of a building or in an opening adjacent to the side walk or roadway or at cross roads; and movably mounted to

traverse the supporting surface and in designating relation respectively with the signs or cards supported by or attached thereto, are the indicating elements 12 consisting in the construction illustrated, of hands or pointers carried by an indicator 13 movable perpendicularly with relation to the rack in suitable guides 14.

A motor of the windmill type is indicated at 15, the same being provided with a driving shaft 16 and with a crank 17 which is connected by a link 18 with the upper end of a swivel rod 19 mounted in suitable bearings 20 and 21, the frame work 22 which supports the wind wheel and its shaft 16 being carried by a revoluble head 23 mounted upon said swivel rod and extended to form a vane 24 by which the wind wheel is maintained in proper position to be actuated by the breeze regardless of the direction in which it may be blowing. The lower end of the swivel rod is connected with the upper end of the indicator bearing 13 by means of a swivel joint 25.

Obviously in the rotation of the wind wheel a reciprocatory movement is communicated through the connecting means to the indicator bearing 13 to cause a corresponding movement of the indicator elements 12 to call attention to the contents of the signs or cards supported by the rack, and when the attention of the passers-by is to be called to the stand, a bell 26 may be suspended in the frame 22 with a parallel spanning arm 27 arranged in the path of an ear 28 carried by the shaft 16. Thus at each revolution of the wind wheel causing a reciprocatory movement of the indicator elements the bell is run to attract the attention which is then specifically directed by the indicating means to the contents of the signs on the supporting rack.

In the modified construction illustrated in Figs. 4 and 5, the sign member or rack 10^a is substantially of the construction heretofore described and the indicator elements 12^a are supported by a pivotal arm 13^a, fulcrumed as at 13^b, and geared by means of beveled pinions 29 to a spindle 19^a mounted in supporting bearings 20^a and 21^a, while motion is communicated to said spindle through beveled gears 30 from a driving shaft 16^a carrying a wind wheel 15^a. An alarm bell 26^a may also be employed in connection with this form of the device to attract attention to the signs and with the

described arrangement of parts, the indicator elements continuously traverse the surface of the rack describing a circular or orbital course with reference thereto.

- 5 It will be obvious that signs constructed as indicated may be produced at a relatively small cost and when erected will require no further attention other than to change the signs from time to time in accordance with 10 the suggestions of the patrons and while it is preferable for reasons of economy to employ a wind motor, as a means for communicating motion to the movable indicating elements, it will be understood that this 15 is a detail which is subject to modification in accordance with the preferences of the dealer.

The invention having been described, what is claimed as new and useful is:—

- 20 1. An advertising display stand having a sign supporting rack, indicating elements movably supported in operative relation with the surface of said rack, a common actuating means for said indicating elements, 25 and a wind motor having a swivel connection with said means and a vane to dispose it in operative relation with the wind, whereby said elements may be actuated irre-

spective of the direction in which the wind is blowing.

30 2. An advertising display stand having a sign supporting rack, indicating elements movably supported in operative relation with the surface of said rack, a common bar carrying said indicating elements, a wind motor having a wind wheel, a swivel rod connecting the shaft of the wind wheel with said supporting bar and an alarm mechanism consisting of a pendent bell having an element arranged in the depth of a tappet 35 on the wind wheel shaft.

3. An advertising display stand having a sign supporting rack, a reciprocable bar mounted upon the rack, indicating elements consisting of pointers carried by the said 40 bar and frame swiveled upon the rack, a wind wheel mounted upon the frame and having a crank shaft, a swivel rod for swiveled connection at one end of said reciprocal bar and connected at the other end 45 with the crank shaft, a pendent alarm bell having an operating bar or ear on the crank shaft for periodically engaging said operating element.

In testimony whereof I affix my signature. 50
RUFUS J. MORTON.
